UNITED STATES PATENT OFFICE.

HARRY JONES, OF SUFFERN, NEW YORK, ASSIGNOR TO THE AMERICAN BRAKE SHOE & FOUNDRY COMPANY, OF WILMINGTON, DELAWARE, A CORPORATION OF DELAWARE.

BRAKE SHOE.

Application filed May 6, 1920. Serial No. 379,199.

To all whom it may concern:

Be it known that I, HARRY JONES, a citizen of the United States, residing at Suffern, in the county of Rockland and State 5 of New York, have invented certain new and useful Improvements in Brake Shoes, of which the following is a specification.

It has been customary for some years to embed metal insert sections or blocks in the 10 cast iron body of brake shoes to prolong the life of the shoe. These insert sections have been made wedge shape in some form to secure anchorage in the body of the shoe. As a result, the area of the insert sections on 15 the wearing face of the shoe is at the minimum when the shoe is new and gradually increases as the shoe wears down in service, while the area of the body metal on the wearing face of the shoe is at the maximum 20 when the shoe is new and gradually decreases with the wear of the shoe. Thus the strength of the shoe decreases as it wears because of the decrease in area of the anchoring body metal and the increase in area 25 of the anchored insert sections.

One of the objects of my present invention is to overcome this defect in the manufacture of brake shoes and to provide a shoe in which there is a comparative increase in the 30 volume of body metal relative to the volume of the insert sections as the shoe wears, and thereby produce a shoe in which the body increases in strength instead of decreasing in strength as the shoe wears.

When the wedge shaped insert sections are embedded in the body with their smaller faces exposed in the wearing face of the shoe, according to previous practice, each insert section transmits the brake pressure 35 applied to the face of the shoe against that part of the body only which is immediately back of the insert section. And as the insert section is wider at the back than at the front and the body portions between the sections 40 are narrower at the back than at the front, a fracture usually occurs in the body at an inner side edge of an insert section.

Another object of my invention is to correct this defect in brake shoe construction 50 by providing insert sections of novel shape and arranging them in the body so that they will distribute brake pressure over a greater area of the body and avoid weakening the shoe in the manner described.

55 I have shown my invention in a selected

form in two kinds of shoes in the accompanying drawings and referring thereto—

Fig. 1 is a side elevation, partly in section, of a car shoe embodying the invention;

Fig. 2 is a sectional view on the line 2—2 60 of Fig. 1;

Fig. 3 is a side elevation, partly in section, of one type of driver shoe embodying the invention;

Fig. 4 is a sectional view on the line 4—4 65 of Fig. 3.

In the drawings, 5 designates the sections or blocks which are cast on or otherwise secured to a plurality of strips 6 of reticulated metal to form a complete insert upon which 70 the body 7 is cast. The insert sections are preferably made of ductile metal but they may be made of any metal or composition suitable for the purpose, and they may be engaged in any suitable manner with the 75 strips so that they will be held in place by the strips in the body. I prefer to use strips made of expanded metal, as shown, but I reserve the right to use wire strips or any other kind of strips which will serve the purpose 80 of anchoring the blocks or sections in the body.

The insert section is of novel shape in the 85 brake shoe art, being tapered inwardly and having its larger face 8 exposed in the wearing face of the shoe and its smaller face 9 embedded in the body. The sides 10 of the section incline from the outer face 8 inwardly and merge into the edges of the rounded inner face 9 so that in cross-section 90 the block or insert is substantially dome-shaped in appearance.

The advantages of my invention will be 95 readily appreciated by those skilled in the art. The maximum area of the insert sections is exposed in the wearing face of the shoe and is brought into contact with the wheel when the shoe is new, and at this time the body is of maximum strength. My insert sections are wider at the front than at 100 the back and the body portions between the inserts are wider at the back than at the front so that as the shoe wears in service the volume of body metal increases as compared with the volume of insert metal and 105 the surface area of body metal increases as the surface area of insert metal decreases. The insert sections transmit brake pressure to the body back of them but their tapering sides distribute the pressure to the body at 110

the sides of the sections. This wide distribution of brake pressure around the two sides and back of the sections and the tapering shape of the sections and the absence of sharp edges on the embedded face and sides of the sections avoids the tendency of the body to fracture which is incident to the use of wedge shaped blocks or sections tapering outwardly. As the shoe decreases in cross section by wear the body increases in volume as compared with the insert sections and this means a comparative increase of strength for the shoe, the importance of which is apparent.

I have found in practice that a brake shoe embodying my invention has greater strength throughout its life and is less likely to fracture than shoes made with wedge shaped blocks or sections tapering outwardly. It is especially important that the maximum insert area be present in the wearing face when the shoe is new and at its maximum strength and this I am able to accomplish because I do not have to depend upon the shape of the insert section to secure anchorage in the body.

The invention may be embodied in brake shoes of other types than those illustrated and in other forms than the preferred form herein described, and I reserve the right to make any changes in the construction and arrangement of parts, and the materials of

which the parts are made, as fall within the scope of the following claims:

1 claim:

1. A brake shoe comprising a body having a plurality of insert blocks or sections embedded therein, said blocks or sections being elongated to extend transversely of the body and spaced apart longitudinally of the body, and each of said inserts being substantially dome-shaped in cross section and having a rounded inner face merging into sides which diverge to the outer face.

2. A brake shoe comprising a body having a plurality of elongated insert blocks or sections embedded transversely in the body and spaced apart longitudinally of the body, said inserts being substantially dome-shaped in cross section, and means embedded in said inserts and said body for holding the blocks or sections in the body.

3. A brake shoe comprising a body having a plurality of elongated insert blocks or sections embedded transversely in the body and spaced apart longitudinally of the body, said inserts being substantially dome-shaped in cross section, and a plurality of reticulated metal strips embedded in said blocks or sections and in said body on edge to the wearing face of the shoe for holding the blocks or sections in the body.

HARRY JONES.
